His Attorney.

UNITED STATES PATENT OFFICE

2,633,548

ELECTRIC INCANDESCENT LAMP

Leonard F. Kramel, Lyndhurst, Ohio, assignor to
General Electric Company, a corporation of
New York

Application January 25, 1951, Serial No. 207,777

6 Claims. (Cl. 313—113)

1

My invention relates in general to electric incandescent lamps and similar devices, and more particularly to a filament instead and supporting structure for lamps of the type employing an envelope comprising two pressed glass sections fusion-sealed together at their rims.

Electric incandescent lamps of the so-called "sealed beam" type are in general use at present for many purposes, such as for automotive headlights and airplane landing lights, for example. Such lamps generally comprise an envelope or bulb composed of pressed glass reflector and cover sections fusion-sealed together at their rims. The lead-in conductors for the lamp filament are generally sealed through the reflector section by means of small metal caps or thimble-like ferrules which cover openings in the wall of the reflector section and are fusion-sealed at their thin rim edges to the glass bordering the said openings. Secured to the inner sides of the ferrules, as by soldering for instance, are the inner lead-in conductors which are connected to and support the lamp filament accurately in place, while at their outer sides the said ferrules are provided with terminals, binding screws, or the like, for connecting the current supply wires thereto. The sealing of the lead-in conductors to the glass envelope is thus effected at the rims or edges of the metal ferrules. Usually, an exhaust tube is also provided as an integral part of the glass reflector section for evacuation of the lamp envelope.

In order to assure an effective seal between the glass and the metal ferrules in such type lamps, it is necessary that the ferrules be made of a material having a coefficient of expansion more or less matching that of the glass to which it is sealed and that it have the ability to readily "wet" and adhere to the glass. For this reason, therefore, it has been heretofore necessary to make the metal ferrules of a special relatively expensive chrome-iron alloy. Moreover, the insertion and sealing of these ferrules into the glass reflector section is performed separately from the sealing together of the reflector and cover glass sections and thus constitutes an additional operation, adding to the manufacturing cost of the lamp.

It is an object of my invention, therefore, to provide an electric incandescent lamp or similar device of the above-mentioned general type which is of simple and relatively inexpensive construction and which is easy to fabricate.

Another object of my invention is to provide an electric incandescent lamp or similar device of the abovementioned general character but employing instead conventional type lamp lead-in conductors or wires, and the sealing-in of which conductors through the wall of the lamp envelope is combined and performed simultaneously with the sealing together of the separate glass parts of which the envelope is formed.

2

According to the invention, the lead-in conductors are sealed through the fused seal joining the reflector and cover glass sections of the lamp envelope and are, in addition, provided with support brace portions or extensions which project into and engage the walls of indentations in the envelope wall to thereby anchor the inner end portions of the conductors and fixedly position the lamp filament accurately in place in the envelope relative to the reflector thereof.

Further objects and advantages of my invention will appear from the following description of species thereof and from the accompanying drawing.

15 In the drawing, Fig. 1 is a sectional view of an electric incandescent lamp comprising my invention; Figs. 2 and 3 are fragmentary perspective views of two different modified forms of mount constructions for the lamp of my invention; and Fig. 4 is an exploded fragmentary sectional view showing the two glass parts of the lamp envelope and a lead-in conductor in position prior to the formation of the fused seal therebetween.

20 Referring to the drawing, the lamp there shown comprises a bulb or envelope 1 consisting of a preformed concave glass reflector section 2 and a preformed cover glass section 3 fusion-sealed together at their rims to form the envelope. The two envelope sections 2 and 3 are made of 25 pressed glass and are provided at their rims with outwardly extending flanges 4 and 5, respectively, having upstanding sealing ridges 6 and 7 (Fig. 4) which are fusion-sealed together. The inner surface 8 of the reflector section 2 is shaped as an optical reflector surface of revolution, such as a paraboloid for instance, and it is provided with a suitable reflective metallic coating 9, such as aluminum or silver, to constitute it a reflecting surface. An exhaust tubulation 10 is provided at the apex of the reflector section 2 for evacuation and, if desired, gas filling the lamp envelope 1, after which operations the said tubulation is tipped-off as shown at 11 to thereby hermetically seal the envelope.

30 Sealed within the lamp envelope 1 is a mount structure 12 comprising a pair of relatively rigid lead-in conductors or wires 13, 13 connected adjacent their inner ends to an electrical energy translation element, or a concentrated light source or filament 14, such as a coiled or coiled-coil wire of tungsten or other suitable refractory metal. In the particular case shown, the filament 14 is in the form of a linear coil extending transversely of the axis X of the reflecting surface 9 through the focus F thereof.

35 In accordance with the invention, the lead-in conductors or wires 13, 13 are sealed through the fused seal joining the reflector and cover glass sections 2, 3 together at their rims. For this purpose, the conductors or wires 13, 13 are preferably of the conventional multi-section type comprising inner and outer leads 15 and 16, respec-

tively, joined end-to-end by and butt-welded to an intermediate seal lead 17 made of a suitable metal which has a coefficient of expansion more or less matching that of the particular glass of which the reflector and cover glass sections 2, 3 are formed and which will readily "wet" and adhere to such glass. For a hard heat-resistant glass of the well-known borosilicate type, the seal lead portions 17 of the conductors 13 may be made, for instance, of tungsten or molybdenum, or of an iron-nickel-cobalt alloy, or a nickel or chrome-iron alloy. The inner and outer lead portions 15 and 16 are preferably made of a suitable less expensive material, such as iron or nickel-plated iron for instance. The seal and inner lead portions 17 and 15, respectively, of the conductors 13 are, in addition, made of a sufficiently large diameter (for example, 10 to 80 mils or thereabouts) to be relatively rigid and thus hold and support the filament 14 in position at all times in the envelope 1.

From the points where they are sealed through the fused seal joining the envelope sections 2, 3, the lead-in conductors 13, 13 extend more or less radially inward of the envelope 1, i. e., toward the axis X of the reflector section 2, and are suitably connected to the opposite ends of the filament 14, as by welding or clamping, for instance. In the case of a single filament lamp such as illustrated, the two conductors 13, 13 therefor are preferably sealed through the fused seal between the envelope sections 2, 3 at diametrically opposite points thereof, and they extend inwardly therefrom preferably in a common radial plane approximately including the reflector axis X.

To brace or anchor the inner ends of the lead-in conductors 13, 13 in place against movement, and to also accurately locate and fix the filament 14 in predetermined position relative to the reflecting surface 9, the lead-in conductors 13 are, in accordance with the invention, provided at their inner ends with brace means or support brace portions 18 which extend into and bear against the walls of locating indentations or dimples 19 formed in the inner surface 8 of the reflector section 2. In the particular form of the invention shown in Fig. 1, the support brace portions 18 are in the form of inner extensions of the lead-in conductors 13, 13, the latter being suitably bent to provide such support brace portions. As shown, the support braces 18 extend in the same general direction as the reflector axis X and, in the case of a single filament lamp such as illustrated, they are also preferably located approximately in the same common plane with the inner lead portions 15 of the conductors 13. If desired, the mount 12 may be rigidified, and formed as a unitary structure to facilitate handling thereof as a unit during fabrication of the lamp, by means of an insulative bridge or tie member 20 fastened across the brace wires 18 and comprising either a glass bead or button embedding the brace wires or, as shown, a short length of glass rod 21 or other suitable insulative material carrying at each end a pair of support wires 22 which are welded or otherwise fastened to the brace wires 18.

In fabricating the lamp according to the invention, the two glass sections 2, 3 are assembled and held in proper sealing relation, with their sealing ridges 6, 7 closely adjacent or abutting one another and the mount 12 positioned and held in place with the seal portions 17 of the lead-in conductors 13 extending between the sealing ridges 6, 7 and the ends of the brace wires or

conductor extensions 18 extending into and bearing against the walls of the locating indentations or dimples 19 in the reflector section 2. To assist in holding the mount in place during the sealing operation and permit the sealing ridges 6, 7 to abut one another, the sealing faces of the sealing ridges 6, 7 are preferably provided, respectively, with matching cross grooves 23 and 24 (Fig. 4) which, when the ridges are abutted, together form a through passageway for the conductors 13 substantially conforming to the cross-sectional configuration thereof. The ridges 6, 7 of the assembled envelope sections 2, 3 are then suitably heated and softened, as by means of gas fires for instance, to thereby cause the glass of the sealing ridges to fuse together and at the same time embed and seal the conductors 13 therein. In the case of a single filament lamp such as illustrated, the conductor-locating grooves 23, 24 in the sealing ridges 6, 7 are preferably located in approximately the same radial plane of the reflector section 2 as the brace wire anchoring indentations 19 in the reflector section.

In the modification of the invention shown in Fig. 2, the filament 14 is clamped to the lead-in conductors 13 instead of being welded thereto as shown in Fig. 1. For this purpose the lead-in conductors 13 are formed with a double bend to provide hooks 25 within which the ends of the filament 14 are clamped.

The modification shown in Fig. 3 differs from the previous forms of the invention in that the support brace means for the inner ends of the lead-in conductors 26 are formed by separate wire members 27 which are suitably secured to the conductors, as by welding for instance. In the particular construction shown in Fig. 3, the brace wires 27 themselves, rather than the conductors 26, are connected to the ends of the filament 14, they being provided for such purpose with hooks 28 within which the filament ends are clamped. It will be understood, however, that if desired the filament 14 could be connected directly to the lead-in conductors 26 instead of to the brace wires 27, and that the connections between the filament 14 and the brace wires 27 or conductors 26 could be effected by means other than the clamping connection illustrated, e. g., by welding.

While the invention has been illustrated only in connection with a single filament lamp, it will be obvious that it is applicable as well to a multi-filament lamp. In such case, the individual lead-in conductors are preferably each provided with individual support brace portions or extensions 18 or 27 which extend into and bear against the walls of corresponding locating indentations or dimples 19 in the inner surface 8 of the reflector section 2.

It will be evident that the engagement of the support brace portions 18 of the mount 12 with the indentations 19 in the reflector section 2 not only serves to anchor and hold in place the inner ends of the lead-in conductors, but also to locate and fix the filament 14 in predetermined position relative to the reflecting surface 9 during the sealing-in of the mount 12 as well as during the subsequent use of the lamp. It is also apparent that the lamp construction of the invention is relatively simple and inexpensive, and that by sealing the lead-in conductors of the lamp in the fused seal joining the reflector and cover glass sections the sealing-in of such conductors in the lamp envelope may be performed concomitantly with the sealing together

of the envelope sections 2, 3, thus eliminating the need for separate sealing operations such as are required in the manufacture of conventional type "sealed beam" lamps as described previously. The manufacture of the lamp according to the invention is thereby considerably simplified.

Although preferred embodiments of my invention have been disclosed, it will be understood that the invention is not to be limited to the specific construction and arrangement of parts shown, but that they may be widely modified within the spirit and scope of my invention as defined by the appended claims.

What I claim as new and desire to secure by Letters Patent of the United States is:

1. An electric lamp or similar device comprising a sealed envelope including a glass reflector section and a glass cover section joined together at their rims by a fused seal, an electrical energy translation element within said envelope, and a pair of relatively rigid lead-in conductors sealed through the said fused seal and connected to the said translation element, said reflector section having its inner surface formed with a locating indentation therein, and said lead-in conductors being provided adjacent their inner ends with relatively rigid brace means extending into and bearing against the wall of said indentation to thereby anchor and position the said inner ends of the conductors in place within the envelope and accurately locate and maintain the said translation element in predetermined optical position relative to the reflecting surface of the reflector section.

2. An electric lamp or similar device comprising a sealed envelope including a glass reflector section and a glass cover section joined together at their rims by a fused seal, an electrical energy translation element within said envelope, and a pair of relatively rigid lead-in conductors sealed through the said fused seal and connected to the said translation element, said reflector section having its inner surface formed with a pair of locating indentations therein, and said lead-in conductors being provided adjacent their inner ends with relatively rigid support brace portions extending into and bearing against the walls of said indentations to thereby anchor and position the said inner ends of the conductors in place within the envelope and accurately locate and maintain the said translation element in predetermined optical position relative to the reflecting surface of the reflector section.

3. An electric lamp or similar device comprising a sealed envelope including a glass reflector section and a glass cover section joined together at their rims by a fused seal, filament means within said envelope, and a plurality of lead-in conductors sealed through the said fused seal and connected to the said filament means, said reflector section having its inner surface formed with locating indentations corresponding in number to said conductors, and said conductors being provided adjacent their inner ends with support brace portions extending into and bearing against the walls of respective ones of said indentations to thereby anchor and position the said inner ends of the conductors in place within the envelope and accurately locate and maintain the said filament means in predetermined optical position relative to the reflecting surface of the reflector section.

4. An electric lamp or similar device compris-

ing a sealed envelope including a glass reflector section and a glass cover section joined together at their rims by a fused seal, an electrical energy translation element within said envelope, and a pair of relatively rigid lead-in conductors sealed through the said fused seal and connected to the said translation element, said reflector section having its inner surface formed with a pair of locating indentations therein, and the inner ends of said lead-in conductors extending into and bearing against the walls of respective ones of said indentations to thereby anchor and position the inner end portions of said conductors in place within the envelope and accurately locate and maintain the said filament means in predetermined optical position relative to the reflecting surface of the reflector section.

5. An electric lamp comprising a sealed envelope including a concave glass reflector section and a glass cover section joined together at their rims by a fused seal, a filament mounted within said envelope in predetermined optical position relative to the reflecting surface of said reflector section, and a pair of lead-in conductors sealed through the said fused seal and extending inwardly therefrom toward the axis of said reflector section and connected to the said filament, said reflector section having its inner surface formed with a pair of locating indentations disposed adjacent the reflector axis, and said conductors being provided with rigid support brace portions extending in the general direction of the reflector axis into respective ones of said indentations and bearing against the walls thereof to thereby anchor the inner end portions of said conductors and position and maintain the filament in said predetermined optical position.

6. An electric lamp comprising a sealed envelope including a concave glass reflector section and a glass cover section joined together at their rims by a fused seal, a filament mounted within said envelope in predetermined optical position relative to the reflecting surface of said reflector section, a pair of lead-in conductors sealed through the said fused seal at diametrically opposite points thereof and extending inwardly therefrom toward the axis of said reflector section and connected to the said filament, said reflector section having its inner surface formed with a pair of locating indentations disposed on opposite sides of and adjacent the reflector axis and said conductors being provided with rigid support brace portions extending in the general direction of the reflector axis into respective ones of said indentations and bearing against the walls thereof to thereby anchor the inner end portions of said conductors and position and maintain the filament in said predetermined optical position, and an insulative bridge member fastened across the said support brace portions of the conductors and tying them together.
